UNITED STATES PATENT OFFICE.

FRED E. WHITE AND FREDERICK E. HOOPER, OF GARDNER, MASSACHUSETTS, ASSIGNEES
TO CENTRAL OIL & GAS STOVE COMPANY, OF GARDNER, MASSACHUSETTS, A COR-
PORATION OF MASSACHUSETTS.

OIL-STOVE.

1,201,902.

Specification of Letters Patent.

Patented Oct. 17, 1916.

Application filed May 27, 1916. Serial No. 100,394.

To all whom it may concern:

Be it known that we, FRED E. WHITE and FREDERICK E. HOOPER, both citizens of the United States, and residents of Gardner, 5 Massachusetts, have invented certain new and useful Improvements in Oil-Stoves, of which the following is a specification.

Our invention relates to an oil burner using a wick of the white flame type, in 10 which the flame burns from the side of the wick and the wick is provided with a stop for limiting its upward movement, the stop being freely removable with a perforated central air distributer to which the stop is 15 loosely connected.

We are aware that it is generally known to provide a wick oil stove with a stop for the wick so as to limit the upward movement of the wick and to provide a central 20 air distributer perforated to supply air to the flame, and, to provide one or more flanges above the wick stop, such a construction being shown in the patent of Berge, 739,143, September 15, 1903.

25 The patent of Robins, 514,036, February 6, 1894, also shows a form of wick stop and a perforated air distributer, while patent to Williams, 662,583, November 27, 1900, shows a wick stop connected to a perforated 30 spreader, which spreader in turn carries deflecting flanges.

Our improvements have to do with this general type of stove, namely, in which a wick stop is used carried by a perforated 35 cylindrical distributer and having a flange or flanges either intermediate of the ends of the distributer or located at the upper ends of the distributer for deflecting the air outwardly, but principally consists in the de- 40 tails of construction, differing from the art referred to in that the distributer carries loosely the wick stop and also carries locking means effective on the raising of the wick to limit the upward movement thereof 45 but automatically detachable when the distributer itself is lifted by hand for the purpose of access to the central air tube as for cleaning.

Our invention is not limited to any par- 50 ticular type of spreader or air distributer, nor do we restrict ourselves to any particu-

lar type of oil reservoir as we show two forms in the drawings accompanying this application.

In these drawings—Figure 1 is an elevation of a reservoir of one type to which our invention is shown as applied; Fig. 2 is a sectional view showing the air distributer and wick stop with parts in elevation; Fig. 3 is a like view with the distributer ready for removal; Fig. 4 is a view a quarter turned from Fig. 3, showing the wick stop and air distributer detached; Fig. 5 is a modification of the oil reservoir.

In these figures the reservoir A is of the ordinary type and as shown in Fig. 2 the wick tubes b' extend through the same terminating in a closed pocket some distance beneath the bottom of the reservoir, the oil being fed to the wick tube through openings 70 a, in the outer wall of the wick tube near the bottom of the reservoir. Instead of this well known type of reservoir and wick tube we may, as shown in Fig. 5, provide only an inner tube b'' within the reservoir B and 75 allow the wick to extend into the reservoir without being fully covered, the upper end of the wick only passing between two annular walls, the outer one extending only part way down, as shown at c c'. In this case 80 we may form the reservoir as shown in Fig. 5, with a depressed central portion d' terminating on a level with the bottom of the tube b''.

As is well known, it is very desirable in 85 the type of burner in which the flame burns from the exposed side of the wick, to have a stop to limit the upward movement of the wick to a previously adjusted position which will give the very best results with- 90 out smoking and without undue charring of the wick, and it is also desirable that this stop be readily removable for the pur- 95 poses of cleaning or for gaining access to the interior of the stove for other purposes. To this end we utilize a perforated air dis- 100 tributer d, which is of ordinary construction preferably having a protruding shoulder e and extending flanges f, g, all of which are old and well known for distributing the air to the flame. The wick stop h is loosely secured to the air spreader or distributer

by a rod *i*, connected at its ends to the body of the wick stop and passing through elongated slots *k*, in the imperforate part of the spreader *d*, so as to have limited movement up and down in relation thereto. The upper part of the wick stop is turned over to provide a flange *l* and perforations are provided directly beneath the flange. The upper end of the wick stop is slightly flared outwardly forming a recess *m*, and this is covered by the narrow flange *e* when the parts are at rest in normal position in the lamp or stove. Within the central draft space a skeleton frame *n* is secured with the central part *o* supported by arms *p*, and the central part acts as a catch over the edges of which the latches *r*, engage as shown in Fig. 2 when the parts are in normal position, these latches being pivoted to the rod *i* and having their upper ends formed with triangular shaped openings as shown in the figures at *s* which engage a staple *t* so that in the upward movement of the spreader *d* the latches *r* are opened and disengage from the disk *o*, enabling the spreader and its attached wick stop to be lifted and removed from its position within the draft tube. When, however, the parts are in normal position as shown in Fig. 2 the latches are under the disk, and when the wick raiser is turned the wick comes in contact with the flange *l* of the wick stop raising the same to the predetermined limit which is the difference between the normal position of the latches in relation to the disk *o*, when the shoulders of the latches are some distance below the disk and the position which the latches assume when the wick stop is lifted to bring the shoulders of the latches in direct contact with the disk. In other words, there is a certain amount of movement that the wick stop and its support may be given vertically before the latches engage the disk at which point the movement comes to a stop and so long as the upward pressure is through the flange of the wick stop by means of the wick there is no disconnection, but when the flange *g*

is grasped and lifted as in Fig. 4 the latches 50 are immediately spread apart as in Fig. 3 and the distributer with its wick stop is readily lifted.

We also utilize an outer perforated shield *u*, this being of ordinary construction and 55 location.

What we claim is:—

1. In combination with an air distributer, a wick stop having vertical movement, a locking device for limiting said movement, 60 and means for releasing said locking device for the removal of the wick stop, substantially as described.

2. In combination with an air distributer, a wick stop loosely connected therewith and 65 having vertical movement therewith, with locking means for the said parts automatically detachable when the air distributer is manually lifted, substantially as described.

3. In combination, a wick stop having an 70 outwardly flared upper end terminating in a projecting flange, an air distributer having a loose connection with the wick stop, a pair of pivoted latches and means for giving lateral movement to the lower ends of 75 the latches in the manual lifting of the air distributer to unlatch the same from a fixed part of the burner, substantially as described.

4. In combination in a lamp stove, an air 80 distributer, a wick stop connected to the air distributer by a rod secured in the walls of the wick stop and extending through slots in the walls of the air distributer, latches 85 pivoted on said rod and having their upper ends slotted, and in connection with a fixed part of the air distributer, and a catch carried by a fixed part of the burner under which the ends of the latches pass, and with which they engage on the raising of the 90 wick stop but from which they are disengaged by the initial lifting of the air distributer, substantially as described.

In testimony whereof, we affix our signatures.

FRED E. WHITE.
FREDERICK E. HOOPER.
